Primary Examiner — Rashida C. Walshon(74) *Attorney, Agent, or Firm* — Mendelsohn Dunleavy, P.C.(57) **CLAIM**

The ornamental design for a clog, as shown and described.

DESCRIPTION

FIG. 1 is perspective view of the top of the clog; FIG. 2 is a perspective view of the bottom of the clog of FIG. 1;

FIG. 3 is an anterior (front) view of the clog of FIG. 1;

FIG. 4 is a posterior (rear) view of the clog of FIG. 1;

FIG. 5 is a lateral view of the clog of FIG. 1;

FIG. 6 is a medial view of the clog of FIG. 1;

FIG. 7 is a top view of the clog of FIG. 1;

FIG. 8 is a bottom view of the clog of FIG. 1; and, FIG. 9 is a cross-sectional view of the clog of FIG. 1, taken along lines 9-9 in FIG. 1.

The embodiment of the clog shown in FIGS. 1-9 are for a left foot. The embodiment of the clog for a right foot is a mirror image of the embodiment shown in FIGS. 1-9 about a sagittal plane of a human body.

The dashed broken lines of equal lengths around the hatched portions of FIG. 9 represent an unclaimed boundary of the design.
